Primary Examiner — Thomas Johannes*Assistant Examiner* — Lauren D McVey(74) *Attorney, Agent, or Firm* — Justin M. Tromp(57) **CLAIM**

The ornamental design for a toner cartridge, as shown and described.

DESCRIPTION

FIG. 1 is a front, right side, top perspective view of a toner cartridge, showing our new design;

FIG. 2 is a rear, left side, top perspective view thereof;

FIG. 3 is a front, left side, bottom perspective view thereof;

FIG. 4 is a rear, right side, bottom perspective view thereof;

FIG. 5 is a front elevation view thereof;

FIG. 6 is a left side elevation view thereof;

FIG. 7 is a rear elevation view thereof;

FIG. 8 is a right side elevation view thereof;

FIG. 9 is a top plan view thereof; and,

FIG. 10 is a bottom plan view thereof.

The broken lines immediately adjacent the shaded areas represent the bounds of the claimed design while all other broken lines are directed to environment. In addition, the unshaded surfaces which directly adjoin the claimed solid line edges form no part of the claimed design.
